UNITED STATES PATENT OFFICE.

SIMON LAKE, OF MILFORD, CONNECTICUT.

SUBMARINE OR SUBMERSIBLE BOAT.

Application filed July 7, 1917. Serial No. 179,183.

To all whom it may concern:

Be it known that I, SIMON LAKE, a citizen of the United States, residing at Milford, in the county of New Haven and State of Connecticut, have invented certain new and useful Improvements in Submarine or Submersible Boats, of which the following is a specification.

The invention relates to improvements in submarine or submersible boats of that class constructed of a plurality of tubular hull sections, and has for its object to provide such a boat of shipshape form to permit of the fair lines for surface navigation, and to withstand the pressures incident to submergence, the invention being particularly designed and adapted for carrying cargoes in bulk, such as wheat, sugar, oils, and other expansible commodities, and which shall be designed and adapted to provide great hull strength and displacement, and to insure a maximum degree of safety, cruising range, surface and submerged speed, and which shall possess great longitudinal strength when operating upon the surface under "hogging" and "sagging" stresses, the construction and arrangement being such as to provide greater longitudinal strength; greater stability, both for surface and submerged operation; a greater maximum degree of safety, and greater seaworthiness than boats of the same general type as heretofore constructed.

The invention relates particularly to improvements in the constructions shown in United States Letters Patents Nos. 756,030; 926,007, and 1,169,970, granted to me March 29, 1904; June 22, 1909, and February 1, 1916, respectively.

The invention consists in the novel construction of a submarine or submersible boat composed of a plurality of longitudinally arranged hull sections, each being of sufficient strength to withstand the maximum pressure of submergence for which the boat is designed, and in the novel arrangement of a longitudinally disposed control compartment of substantially cylindrical form in cross section, and in the arrangement of substantially cylindrical passageways connected to said control compartment and to said hull sections, said control compartment and said passageways providing a longitudinal girder well above the neutral axis of the boat, thereby not only providing greater strength when operating under "hogging"

and "sagging" stresses, but also a construction affording greater comforts for the personnel than in boats of this general type as heretofore constructed, the construction and arrangement being such that access may be had between the control compartment and the longitudinal passageways, and to the several compartments of the boat as will be hereinafter described. The invention further consists in the peculiar and novel arrangement of a central, longitudinally arranged water ballast compartment, combined with means for controlling the contents of the several ballast compartments of the main hull, whereby the said ballast compartments may be maintained completely filled under varying changes of temperature, and especially when carrying cargoes of oil and other expansible commodities.

The invention further consists in the peculiar and novel arrangement of an anchor hoisting compartment arranged within the bow of the boat and having communication with the control compartment, and in the peculiar arrangement of a tiller compartment arranged in the stern section of the boat and also having communication with the said control compartment, and further, in the provision of means whereby access between the said compartments and the aforesaid communicating passageways of the boat may be controlled.

The invention still further consists in the peculiar and novel construction of main bulkheads arranged throughout the main hull sections of the boat, in the peculiar and novel arrangement of strengthening members arranged within the main hull sections, and in certain other novel features of construction and arrangements of parts as will be hereinafter fully described and then claimed.

In the drawings, illustrating the invention, in the several figures of which like parts are similarly designated, Figure 1 is a diagrammatic longitudinal section drawn through the after end of the boat on the line *a—a* of Fig. 7 of the drawings. Fig. 2 is a similar view drawn on the same line of the forward end of the boat. Fig. 3 is a diagrammatic longitudinal section drawn through the after end of the boat on the line *b—b* of Fig. 7. Fig. 4 is a diagrammatic longitudinal section of the forward end also drawn on the line *b—b* of Fig. 7. Fig. 5 is a horizontal sectional plan view of the after

section of the boat. Fig. 6 is a similar view of the forward section of the boat. Fig. 7 is a transverse section drawn on a larger scale through the main hull sections and 5 through the control compartment of the boat. Fig. 8 is a transverse section drawn through the main hull sections and through the after communicating passage and through the engine and battery compartments of the boat. Fig. 9 is a transverse section drawn on the line *c-c* of Fig. 2 of the drawings looking in the direction indicated by the arrows. Fig. 10 is a detail 10 arrangement for filling the main cargo carrying tanks of the boat when designed for carrying liquid cargoes.

The boat is preferably constructed of two parallel main hull sections 1, substantially 20 cylindrical throughout their length and having upwardly inclined tapered bow and stern sections 2 and 3, respectively, said sections being of gradually diminishing sizes and preferably of circular form, and 25 from which extend platings 2' and 3', to provide for a shipshape form of hull best adapted for surface cruising. The said hull sections are connected throughout their length by suitable truss frames (not shown), 30 whereby the said sections are rigidly joined to form a unit, it being, of course, understood that the said hull sections 1 are constructed of ribs 1' (Figs. 7 and 9), and shell plating 1" in the usual manner. The hull 35 platings 1" of the main hull sections are connected by a horizontally arranged divisional plate 4, Figs. 7 and 9. The bottoms or lower surfaces of said hull sections are connected by a plate 5 forming the bottom 40 of the boat, the space thus formed between the inner sides of the main hull sections and the plate 4 and plate 5 provides a longitudinal compartment 7 extending throughout the entire length of the main hull sections 1. 45 Connected to the main hull sections 1, and to the bottom plate or plates 5, are longitudinal vertically arranged beams 6, extending throughout practically the entire length of the hull of the boat, and which 50 serve to provide the said central longitudinally extending compartment 7, said compartment being divided by transverse partitions 9 into a plurality of compartments 9', which may be utilized for various purposes in the operation of the boat. The 55 space formed between the after transverse partition 9 and bulkhead 9", closing the space at the end of the main hull sections, provides a battery compartment 10 in which 60 are arranged battery cells 10' for operating the boat under submerged conditions. It 65 will be understood that the longitudinally arranged beams 6 will be perforated throughout their length to afford communication with the compartments 8, designed to

receive water ballast, and also to provide communication between the said longitudinal compartment 7 and the lateral compartments 8. Between the partitions 9, forming the battery compartment and various other compartments which it might be desired to maintain water-tight, the said beams 6 will be of solid construction, so that a plurality of water-tight compartments may be provided throughout the length of the boat, the said water-tight compartments being so distributed as to serve to the best advantage in the operation of the boat, such, for instance, as for the installation of pumping apparatus, air bottles, fuel tanks, storage tanks for fresh water, and other apparatus or articles, and into which access may be desired under various conditions of the operation of the boat. It will also be understood that by the arrangement of the lateral water channels or compartments 8, there is open communication between the several intermediate compartments 7 and the lateral compartments 8, thereby eliminating a plurality of valves for controlling the admission of water to and the expulsion of water from the central compartment 7, as would be the case were the several compartments 9' completely cut off from each other. 95

The main hull sections 1 are divided throughout their length by bulkheads 11, preferably arranged in pairs of concavo-convex form in cross section having their concave surfaces arranged opposite each other whereby to provide greater strength to the hull sections. The ends of the main hull sections 1 are closed by similar bulkheads 12, and the spaces 13, formed between the after bulkheads 12 and the adjacent bulkheads 11, provide engine compartments in which are arranged engines 14, shown diagrammatically in Fig. 3 of the drawings, the said engines having their shafts extended through the hull of the boat and having propellers at their outer ends in the usual manner. It will, of course, be understood that suitable stuffing-boxes are provided in the bulkheads, and in the plating of the stern of the boat, in accordance with common practice. 100

Extending upwardly from the tops of the main hull sections 1 are side members 15 of a superstructure 16, and connected to the said side members 15 are decks 18 having 110 their longitudinal edges connected to vertical walls 17 extending from the hull platings of the main hull sections, as shown most clearly in Figs. 7, 8 and 9, the said decks 18 forming what I prefer to term a 115 "harbor deck". The said superstructure and the said harbor deck extend from the extreme bow of the boat to a point adjacent to the end of the stern section, as shown in Figs. 5 and 6. There may also be a cruis- 120 125 130

ing deck 19 on top of the superstructure 16, as shown in full lines in Figs. 1, 2, 3 and 4, and as indicated by the dotted lines in Fig. 7, this deck being shown as arranged over the central control compartment next described.

Arranged centrally within the superstructure 16, and having its longitudinal center arranged over the center of gravity and center of buoyancy of the boat, is a central control compartment 20, and from the ends of the control compartment extend substantially cylindrical passageways 21 having communication with the ends of the control compartment 20 through openings 22 controlled by doors 23. The said control compartment is formed with laterally arranged hatchways 24 (Fig. 7), controlled by doors 25, said hatchways opening into the superstructure 16. Hatchways 26 (Fig. 7), may also be provided leading from the central control compartment to the adjacent cargo carrying compartments of the main hull sections, and these hatchways will be closed by hatch covers 27 opening into said control compartment 20. Opening into the several compartments of the main hull sections 1 are hatchways 28 provided with hatch covers 29, said covers being provided with suitable pipe connections 30 for filling the cargo carrying tanks or compartments, and with vents 31, as shown. While I have shown and described an arrangement for filling the several cargo carrying compartments or tanks through the hatch covers, it will, of course, be understood that the filling openings also may be utilized for pumping liquid cargoes from said tanks or compartments, and, if desired, the said tanks or compartments may be filled and emptied through pipes 32 (Fig. 10), extending into the bottoms of said tanks or compartments, and having connections through pipes 33 with suitable pumps (not shown), arranged within the boat, similar to those employed in all submarine boats for pumping water into and out of the ballast tanks, and in a manner somewhat similar to the method of pumping oil into and from surface oil carrying vessels.

Connected to the top of the central water compartment 7 are pipes 34 having their ends extending into and opening into the said hatchways 28. The pipes 34 are provided with valves 35 having their stems extending into the control compartment 20 and into the passageways, and provided with operating handles. Of course, it will be understood that one of such pipes and their valve connections are arranged in each cargo carrying tank or compartment, and serve the purpose of controlling the contents of said tanks or compartments as will be best understood from the general description of the operation of the boat.

Admission of water to the water compartments 7 is controlled by valves 36 (Fig. 7), having their stems extended upwardly through the horizontal divisional plates 4, forming the top of the central water compartment 7, and through the plating of the central control compartment 20, and having their inner ends provided with hand wheels by which the valves 36 are controlled.

The main hull sections 1 are provided throughout their length with keelson beams 37, having their upper ends connected by horizontally arranged plates 38, which may be solid to provide ballast compartments 39, or perforated so as to provide continuations of the several ballast tanks or compartments of the main hull sections 1. In either case, however, it will be understood that the said keelson beams 37 and the said horizontally arranged plates 38 serve to strengthen the main hull sections 1, and from the inner longitudinal edges of the plates 38 there may be extended strengthening plates 40 providing strengthening members upon opposite sides of the water ballast compartment 7, and the spaces adjacent to the several tanks of the boat.

The battery compartment 10 may be thrown into communication with the engine compartments 13 through a passageway 41 extending through the hull platings of the main hulls and having its ends provided with doors or covers 42, and opening through one side of the said passageway 41 is a doorway 43 controlled by a suitable door leading into said battery compartment. The said battery compartment is also arranged in communication with the after passageway 21 through a hatchway 44 controlled by a cover 45, a suitable ladder 46 (shown in dotted lines in Fig. 8), being provided to facilitate entrance to and exit from the battery compartment.

To the platings of the main hull sections, within the compartments 13 forming the engine rooms, there are arranged a plurality of frames 47 (Fig. 8), having their inner members connected air- and water-tight by plates 49, having ends 50 which are also connected air- and water-tight to the hull platings of the main sections 1, whereby to provide compartments 51, which may be utilized either as water ballast compartments, or as fuel compartments for the engines as occasion may dictate.

In the extreme bow section of the boat there is arranged an anchor compartment 52 having access with the forward ends of the passageways 21 through tubular passages or tunnels 53, the entrances to which are controlled by doors 54 controlling openings formed in the bulkheads 12. The said anchor compartment 52 is provided with anchor wells 55 (shown in dotted lines in Fig. 2), which serve to house the anchors when

the boat is operating either upon or below the surface of the water, the said anchors being, of course, supported by suitable anchor cables (not shown), wound upon hoisting drums (not shown), mounted within the anchor compartment 52, it being understood that suitable mechanisms operable from within the anchor compartment, or from within the central control compartment, are 5 arranged for operating the hoisting drums for controlling the raising and lowering of the anchors. Since this feature of the invention is common in submarine boats, and particularly that class shown and described in 10 my United States Letters Patent No. 716,059, I do not deem it necessary to dwell in detail upon this feature of the invention; and while the construction shown in my said Patent No. 716,059 shows the anchor cable 15 wound upon drums on the sides of the conning tower or turret of the boat, it is obvious that similar drums may be arranged within the anchor compartment, and operated either from said compartment, or from 20 the central control compartment, without departing from the broad idea of the invention.

In the stern section of the boat there is located a tiller compartment 60 having suitable connections (not shown) arranged therein for controlling the position of the rudder, and this compartment 60 is connected through a passage tube 61 with the after ends of the after passageway 21, and, 30 like the passageway at the forward end of the forward passage tube, is controlled by a hatch cover or door 62. It will be understood that suitable connections will be made between the tiller compartment and the control compartment for operating the rudder, but as this feature also forms no part of the present invention, it is not thought necessary to show or describe the same.

It will, of course, be understood that the 40 boat, as herein described, will, of necessity, be provided with suitable observation towers, periscopes, and guard rails as is customary in all submarine or submersible boats.

I do not claim the broad idea of constructing a submarine or submersible boat of a plurality of parallel tubular hull sections, since this construction is clearly shown and described in my aforesaid United States Letters Patent No. 926,007, of June 22, 1909, 50 but what I do claim is that the construction shown in the present application provides a form of construction giving greater longitudinal strength than that of an ordinary ship under "hogging" and "sagging" 55 stresses, due to the fact that both the moment of inertia and section modulus of the material entering into the construction of the hull is greater than that entering into the construction of the hulls of other vessels 60 of the same length, breadth, and depth of

hold. The hull is constructed of tubular sections extending throughout the greater part of the boat's length with keelsons of great strength, by which, combined with the upper tubular section, there is provided a 70 construction which serves to take up all tension imposed upon the vessel under "hogging" stresses, and with my special arrangement of deck plates located well above the neutral horizontal axis of the boat, the 75 strains coming upon the vessel under "hogging" stresses, such as occur when riding the crest of a wave, are also taken care of. Also, my novel method prevents the shifting of liquid cargoes of expansible nature, 80 whereby the cargo carrying tanks or compartments may be maintained to their full capacity, or as expressed in nautical terms "chock-a-block", which is an absolutely essential feature of navigation, as it prevents the shifting of the cargo, and hence the excessive pitching or rolling of the vessel, which would otherwise occur when the tanks 85 are only partly filled. This feature of my invention may be best understood from the 90 following description of the general operation of the invention, attention being invited particularly to Fig. 7 of the drawings, in which the central ballast tank 7 is shown 95 provided with water inlet valves 36 open to the sea, and operated from within the central control compartment 20, whereby the flooding of said compartment 7 may be controlled. It is well known that oil expands 100 under rising temperatures. To provide for such expansion, I purpose to first admit a certain amount of sea water into the tank or tanks 7, corresponding to the maximum amount of expansion which may be expected, which depends upon the specific gravity of 105 the cargo. The valves 36 are then closed. Oil may be pumped into the several compartments of the main hull sections 1 with the vents 31 and valves 35 open so that the 110 said compartments may be filled "chock-a-block", after which the said vents are closed and the filling pipes removed. The water inlets 36 to the said compartments are then sealed. This operation, of course, will take 115 place when the several ballast tanks or compartments are being filled through the hatches arranged in the harbor decks of the boat, and when the said ballast tanks or compartments of the boat are being filled or emptied through the pipes 120 32 leading into the bottom sections of the said tanks or compartments, the said inlets 30 connected to the hatch covers 29 will be maintained closed, and the vents 31 will 125 remain open so as to insure the complete filling of the said tanks or compartments. The valve or valves 36 controlling admission to the water channels 7 and 8 may then be open to the sea, and due to the fact of the differences between the specific gravity of water 130

and oil, it will be appreciated that the oil will not run out of the cargo carrying tanks or the water channels 7 and 8, and that the water in the channels 7 and 8 will be forced out as the oil within the several compartments is expanded under increased temperatures, in which case, it will be appreciated that only the amount of water equivalent to the expansion will be forced out of the compartments 7 and 8. Now when the temperature of the oil is reduced, thereby causing a contraction of the contents of the several tanks or compartments, the consequence would be to form a vacuum within the tanks or compartments so that sea water will be drawn into the tanks 7 to thus force the oil in the upper end thereof back into the tanks or compartments of the hull sections 1, thus always maintaining the compartments completely filled, which is essential especially in submarine boats, since it prevents the shifting of the center of gravity of the liquid contents, which would otherwise take place and hence cause difficulty in maintaining the trim of the boat.

It will be noted that the tubular pressure resisting members 1 of the vessel have their forward and after ends connected by the bow and stern sections 2' and 3', which sections are preferably constructed so as to be normally open to the sea, and that the forward and after main hull sections have their axes arranged in upwardly inclined directions so that they will merge fairly into the nonpressure resisting bow and stern sections, to permit of the fairing lines of the boat. It will also be noted that by providing the double bulkheads of the shape described, I provide a plurality of coffer dams throughout and at the ends of the main hull sections so that in the event of injury or an explosion in any one of the several tanks or compartments of the boat, it will be understood that one of the bulkheads will be under tension and the other under compression, hence providing a very strong construction capable of preventing the force of the explosion in any one compartment from extending into the adjacent compartment. Compressed air pipes (not shown), will be extended into the coffer dams and into the several compartments of the boat, whereby water may be blown from and the compartments kept free from water in the event of rupture to the platings of the boat at or near the bottom thereof. It will also be appreciated that the spaces formed by and between the double bulkheads may be used as ballast tanks, or as fresh water tanks, fuel tanks, or for the storage of other commodities carried by the boat.

It will thus be seen that I provide a construction of hull whereby a boat of greater length and of exceptionally shallow-draft commensurate with the length and beam may

be produced, and one that possesses great longitudinal and transverse strength, and particularly adapted for the carrying of liquid cargoes. By this construction also the shifting of liquid cargoes of expandible nature may be prevented or provided for, so that the boat may be maintained upon an even keel when travelling submerged, or in a semi-submerged condition, and whereby is avoided excessive rolling and pitching motion of the ship when operating upon the surface of the water, and furthermore, whereby the longitudinally arranged substantially cylindrical control and communicating compartments, combined with the arrangement of keelsons, is provided a novel form of submarine boat possessing greater advantages and greater strength than that of similar vessels heretofore constructed.

It will, of course, be understood that various strengthening plates, or, in other words, bulkheads, may be arranged throughout the several cargo carrying tanks or compartments to add greater strength to the hull sections, and that the central water compartment 7 may also be provided with suitable longitudinally arranged beams or keelsons 70, as shown in Fig. 9, and which may be connected by transversely arranged perforated bracket plates 71 having their opposite ends connected to the beams 6, thereby providing supports both for the beams or keelsons 70 and the beams 6.

What I claim is:—

1. In a submarine or submersible boat, a plurality of hull sections having a plurality of oil carrying tanks or compartments, a control compartment arranged above and connected to said hull sections and communicating therewith, and means operable from within said control compartment for governing the contents of said tanks or compartments.

2. In a submarine or submersible boat, a plurality of main hull sections having transversely extending passages, means for controlling the said passages, a superposed control compartment connected to and communicating with said main hull sections, bulkheads arranged within said main hull sections providing a plurality of cargo carrying tanks, and means operable from within said control compartment for governing the contents of said tanks, substantially as set forth.

3. In a submarine or submersible boat, a plurality of main hull sections having transversely extending passages, means for controlling the ends of said passages, a superposed control compartment connected to and communicating with said main hull sections, bulkheads arranged within said main hull sections providing a plurality of cargo carrying tanks, means operable from within said control compartment for governing the

contents of said tanks, as specified, and a superstructure extending from said hull sections and surrounding said control compartment.

5 4. A submarine or submersible boat, comprising a plurality of hull sections provided with bulkheads, a central control compartment arranged above said hull sections and communicating therewith, bow and stern sections connected with said hull sections and with said control compartment, an anchor compartment arranged in the bow section of the boat and a tiller compartment arranged in the after section of the boat, and passage-
10 ways affording communication with said anchor compartment and with said tiller compartment.

15 5. A submarine or submersible boat, comprising a plurality of substantially cylindrical hull sections united to each other, a substantially cylindrical control compartment arranged above and connected to said hull sections, and substantially cylindrical sections connected to said hull sections and 20 to said control compartment, said control compartment and said cylindrical sections providing a longitudinal girder above the vertical axis of the boat.

25 6. In a submarine or submersible boat, constructed of a plurality of substantially cylindrical hull sections united to each other, a superposed substantially cylindrical control compartment, and substantially cylindrical passageways connected to the forward, 30 and after ends of said control compartment, said control compartment and said passageways providing a longitudinal girder well above the neutral axis of the boat.

35 7. A submarine or submersible boat, comprising a plurality of independent hull sections united to each other and having plat-
40 tings providing the bottom of the boat, longitudinally arranged beams connecting the platings of said hull sections and said bottom plates providing a central longitudinal water compartment, a substantially cylindrical control compartment arranged above and connected to said hull sections, and substantially cylindrical members extending 45 fore and aft of said central control compartment and communicating therewith, said central control compartment and said cylindrical members providing a superposed girder, substantially as specified.

50 8. A submarine or submersible boat, comprising a plurality of substantially cylindrical hull sections, bow and stern sections connected thereto, bottom platings connected to the platings of said hull sections, longitudinally arranged beams connected to the plating of said hull sections and to said bottom platings, as and for the purpose specified, a superstructure extending from the said hull sections, a control compartment arranged within said superstructure and con-

nected to and communicating with said hull sections, and longitudinally arranged tubular sections connected to and communicating with said central control compartment, said control compartment and said tubular sections providing a longitudinal girder well above the neutral axis of the boat. 70

9 9. In a submarine or submersible boat, a plurality of hull sections united to each other and having bow and stern sections to provide a shipshape structure, platings connecting the lower sides of said hull sections providing a longitudinal water channel, as and for the purpose specified, a superstructure arranged above and connected to said hull sections, a centrally disposed control compartment connected to and communicating with said hull sections, and substantially cylindrical passageways connected to the ends of said control compartment and to said hull sections and communicating with said control compartment and with the said hull sections, said control compartment and said passageways providing a longitudinal girder well above the neutral axis of the boat. 80 85

10 10. A submarine or submersible boat, comprising a plurality of individual hulls containing individual ballast tanks or compartments, a central water compartment communicating with said ballast tanks or compartments, and means for controlling the admission of water to said compartments. 90 95

11 11. A submarine or submersible boat, comprising a plurality of individual self-contained hull sections having a series of individual cargo carrying compartments, an intermediate water compartment, a control compartment arranged above said hull sections, and means for controlling the admission of water to said water compartment and operable from said control compartment. 100 105

12 12. A submarine or submersible boat, comprising a plurality of individual self-contained hull sections having a series of individual cargo carrying compartments, a centrally disposed water compartment communicating with said cargo carrying compartments, said water compartment being disposed below said cargo carrying compartments, a central control compartment arranged above said hull sections, and means operable from within said control compartment for governing the contents of said cargo carrying compartments when said cargo carrying compartments contain expansible cargoes. 110 115 120

13 13. In a submarine or submersible boat, a plurality of self-contained hull sections structurally connected and provided with a harbor deck and a superstructure, a substantially cylindrical control compartment arranged within said superstructure and communicating with said hull sections, and a 125 130

substantially cylindrical passageway extending from each end of said control compartment and communicating therewith and connected to said hull sections substantially as specified.

14. A submarine or submersible boat, comprising a plurality of individual self-containing hull sections, having a longitudinally arranged water compartment located in and by the space formed between said hull sections and communicating with said hull sections, a central control compartment arranged above and connected to said hull sections, and means controlling the admission of water from said longitudinally arranged water compartment to said hull sections.

15. A submarine or submersible boat, comprising a plurality of self-contained hull sections united to each other, and a substantially cylindrical control compartment arranged above and connected to said hull sections and communicating therewith, and substantially cylindrical sections arranged forward and aft of said control compartment and connected therewith and to said hull sections providing a longitudinal girder above the neutral axis of the boat.

In testimony whereof I have hereunto set my hand this 3rd day of July A. D. 1917.

SIMON LAKE.
